UNITED STATES PATENT OFFICE.

WILLIAM H. ALLEN, OF DETROIT, MICHIGAN.

SERVICE-PIPE FOR WATER-STORAGE SYSTEMS, &c.

1,030,447.

Specification of Letters Patent. Patented June 25, 1912.

Application filed October 9, 1905. Serial No. 281,918.

To all whom it may concern:

Be it known that I, WILLIAM H. ALLEN, a citizen of the United States of America, residing at Detroit, in the county of Wayne 5 and State of Michigan, have invented certain new and useful Improvements in Service-Pipes for Water-Storage Systems, &c., of which the following is a specification, reference being had therein to the accompanying drawings.

This invention relates more particularly to service pipes which supply water from a general supply system to water storage systems such as for instance employed in 15 connection with so-called sprinkler systems and other fire extinguishing systems. In storage systems of this character the water is generally stored at a higher level than it can be supplied by the pressure commonly 20 maintained in the water supply systems of cities and whatever means are employed to elevate the water to such higher level they are not proof against leakage, nor can the check valve ordinarily employed in the service 25 pipe be absolutely relied upon to prevent such leakage and thus a slight leakage might constantly take place from the storage system back into the water supply system from which the domestic user derives 30 his supply. Considering the large number of storage systems of this and like character in use in big cities all of which may be supplied from and communicate with the same source, the leakage from these systems consisting mostly of water which has become 35 foul and unwholesome from long standing may become an ever present and unsuspected source of contamination of the water in the supply system and be the direct cause of 40 spreading typhoid fevers and like diseases resulting from the use of impure water.

It is the object of this invention to prevent contamination of the water in the supply system from possible leakage which may 45 take place from a storage system by reason of a leaky check valve in the service pipe when there is a difference in pressures and to this end the invention consists in a system provided with a check valve of a novel 50 character as shown and described in the accompanying drawings, in which—

Figure 1, shows diagrammatically in elevation a fire extinguishing system of general character embodying my invention, and 55 Fig. 2, is a detached section of the check valve.

In the drawings, A represents the street main of a water distributing system; B the service pipe leading therefrom; C the water cisterns into which the service pipe discharges; D the power pump which draws the water from the cisterns through the pipe E, F the elevated storage tank into which the pump discharges, G the sprinkler pipes, H the shut-off valve in the service 60 pipe and I the check valve.

In the normal condition of the fire extinguishing systems shown the pressure of the water in the system is supposed to be considerably higher than that in the street 65 main, and the pump is at a stand still. It is obvious then that this high pressure will be present in the cistern and thus there will be a high pressure opposed against a lower pressure on the check valve I. Instead of 70 this check valve being of the usual character, I use a double check valve as shown in Fig. 2 in which a a' are two valve disks connected by a common valve stem b and provided with seats in the valve casing, the 75 valves when seated coöperating with the casing to form a chamber c, this chamber is provided with a discharge opening d. With a check valve of this character it will be seen that with the valve disks properly 80 adjusted to their seats, there can be no escape of water from the opening d except what may be due to leakage around the valve disks and this will be conducted away 85 provided the leakage is not beyond the capacity of the drain passage d but if it should be the force of the stream issuing 90 from the drainage pipe calls the attention of the engineer at once to the faulty condition of the valve and he can readily ascertain 95 if the leakage comes from the storage side or from that of the supply pipe by closing the valve H. As long as the leakage does not escape under pressure which he can tell by looking at it the valve performs its intended function.

The opening d need be but relatively small, to accomplish the object of my invention since the appearance of water issuing through the opening would indicate the 100 faulty condition of the valve, and it will not interfere with the operation of the fire extinguishing system, since the amount of water which would escape through it in case of the valve being lifted from its seat in the 105 operation of the system would be a negligible quantity.

There should be no cock on the outlet *d* since it might defeat the very object of my invention, on the contrary I permit the free escape and furthermore would arrange it 5 in such way that it would form a visual indicator under the eye of the engineer and form a safe guard in maintaining the operativeness of the fire extinguishing system to which it applies.

10 Having thus fully described my invention, what I claim is:—

The combination with a water supply system adapted to supply the water under pressure and a storage system in communication 15 therewith through a supply pipe and adapted to store the water at a height above that to which it will be supplied by the supply

system, of a stop cock in the supply pipe and an automatic check valve in the supply pipe between the stop cock and the storage 20 system, said check valve comprising two co-acting valve disks of equal area spaced apart and forming in conjunction with their casting a chamber intermediate said valve disks, and a drainage pipe forming an unrestrainable outlet from said chamber into the atmosphere. 25

In testimony whereof I affix my signature in presence of two witnesses.

WILLIAM H. ALLEN.
